UNITED STATES PATENT OFFICE.

ARTHUR J. MOXHAM, OF JOHNSTOWN, PENNSYLVANIA.

RAILWAY-SWITCH WORK.

SPECIFICATION forming part of Letters Patent No. 540,796, dated June 11, 1895.

Application filed March 30, 1894. Serial No. 505,764. (No model.)

To all whom it may concern:

Be it known that I, ARTHUR J. MOXHAM, of Johnstown, county of Cambria, State of Pennsylvania, have invented a new and useful Improvement in Railway-Switch Work, of which the following specification is a true and exact description, due reference being had to the accompanying drawings.

My invention relates to those structures in railway tracks such as mates, crosses or similar structures in which two or more rails converge, forming what is known as a point. This point is a source of much trouble on account of the excessive wear which takes place there due to the fact that the head of the rail reducing in width does not afford the same amount of bearing surface to the wheel as where the rail is whole. In the case of a crossing where there is a groove through the head of the rail for the passage of the flange of a wheel traveling upon the crossing track, and a floor portion or a riser upon which the wheel flange rolls to carry it across the groove, this floor portion is subjected to great wear on account of the narrow edge that the wheel flange presents for a bearing upon it.

The object of my invention is to provide a structure in which that portion subject to this excessive wear may be made of more durable material than the remainder of the structure, and so inserted therein as to be removable, either for realignment or replacing when worn. To form the entire structure of this more durable material or to harden the entire surface of it would be costly and difficult, but a small portion of it may be so treated and then inserted in the body of the structure thus effecting a large saving in the construction of the switch piece.

Referring to the drawings, Figure 1 shows a mate, and Fig. 2 a frog, each in perspective and embodying my invention. Fig. 3 is a top view of the frog, Fig. 2. Fig. 4 is a section on line W W, and Fig. 5 a section on line X X, both of Fig. 3. Fig. 6 is a top view of the mate, Fig. 1. Fig. 7 is a section on line Y Y, and Fig. 8 a section on line Z Z, both of Fig. 6.

As shown, the central portion A having a pocket adapted to receive the plate B is formed by casting it with short projections to which the rails C are welded as at d Fig. 8, or

instead of welding rails thereto the projections may be formed long enough to be joined to the abutting track rails by means of the usual splice bars and bolts. The pocket is formed with two sides inclined, as shown in Fig. 4, so that it is larger at the bottom than at the top. The plate B is also formed wedge shaped, and when inserted in the pocket I pour molten zinc E in the space between the plate and the walls of the pocket. This zinc when its hardens secures the plate firmly in place. I prefer zinc because in hardening it expands and so more firmly secures the plate; but instead of zinc any suitable substance may be used as lead, sulphur or cement.

In the frog Fig. 2 I have shown the plate B as rectangular which shape is preferable to the tapered one used in the mate Fig. 1, as it may be rolled in long lengths or bars having the proper taper on the sides. The plates may be then cut from the bar to the length desired. The grooves on the face of the plate for the car wheel may be made in any suitable manner, as milling or planing, and is preferably done before the plate is secured in the structure.

When at any time it becomes desirable to remove the plate it is readily done by cutting away the zinc at E and lifting the plate out; or, instead of cutting the zinc out the plate might be heated sufficiently to melt it and so allow the removal of the plate.

If desired the plate B may be made of a steel capable of being hardened, and the top surface of it may be case hardened or otherwise rendered more durable before putting it in place, or the plate may be made of cast iron having a chilled top surface. Thus a switch piece is formed having a hardened and more durable surface at the point subjected to the greatest wear, and the life of the structure is thereby prolonged.

Instead of forming the sides of the plate and pocket sloping they may be corrugated or roughened, the object of it being to cause the zinc to exert a holding down force upon the plate.

Should the plate become loose from any cause the soft zinc may be tamped in with a calking iron and thus made to tighten the plate.

Having thus described my invention, what I claim, and desire to protect by Letters Patent, is—

1. A railway switch structure comprising a body portion having the diverging rails secured thereto and having a pocket adapted to receive a plate, a plate in said pocket having flange ways and the point formed thereon and a retaining material between the plate and sides of said pocket whereby the plate is held in position in said pocket.

2. In a railway switch structure in combination with a body portion having a pocket, a plate in said pocket having track surfaces formed thereon and a filling material between the plate and the sides of the pocket.

In testimony whereof I have affixed my signature in presence of two witnesses.

ARTHUR J. MOXHAM.
